UNITED STATES PATENT OFFICE.

EDWARD JAMES HUNT, OF GREENVILLE, OHIO.

SAFETY GATE FOR RAILWAY CROSSINGS.

Application filed March 10, 1924. Serial No. 698,216.

To all whom it may concern:

Be it known that I, EDWARD JAMES HUNT, a citizen of the United States, residing at Greenville, in the county of Darke and State of Ohio, have invented certain new and useful Improvements in Safety Gates for Railway Crossings, of which the following is a specification.

This invention relates to a safety gate for railway crossings, and is designed primarily for use in connection with steam railways but it is to be understood that it is thoroughly applicable for use in connection with electric trolley line crossings as well, and the invention has for its object to provide, in a manner as hereinafter set forth, means actuated by a train as it approaches the crossing for positioning a pair of gate members transversely with respect thereto at each side of the trackway to close the highway to traffic and to prevent traffic crossing the railway track in advance of an on-coming train reaching the crossing, thereby materially reducing accidents to a minimum, and with said means further actuated as the train passes the crossing for the purpose of returning the gate members to normal position to open the highway to traffic.

A further object of the invention is to provide, in a manner as hereinafter set forth, a safety gate and its operating mechanism applicable to a single or a double track railway and so constructed and arranged whereby a highway will be closed to traffic by an on-coming train before it reaches the crossing, and will be opened to traffic when the train has left the crossing.

Further objects of the invention are to provide, in a manner as hereinafter set forth, a safety gate, which is comparatively simple in its construction and arrangement, strong, durable, operated to safety position by an on-coming train towards the crossing, and restored to normal position as the train leaves the crossing, thoroughly efficient in its use, readily installed, and comparatively inexpensive to set up.

With the foregoing and other objects in view, the invention consists of the novel construction, combination and arrangements of parts, as hereinafter more specifically described and illustrated in the accompanying drawings, wherein is shown an embodiment of the invention, but it is to be understood that changes, variations and modifications can be resorted to which come within

the scope of the claims hereunto appended.

In the drawings wherein like reference characters denote corresponding parts throughout the several views:—

Figure 1 is a top plan view of a double track railway and a highway, and further illustrating the adaptation of a safety gate, in accordance with this invention, with respect to the tracks of the railway and the crossing at the highway.

Figure 2 is a view similar to Figure 1, showing the adaptation of a safety gate in accordance with this invention, with respect to a single track railway and highway.

Figure 3 is a fragmentary sectional elevation of the safety gate employed in connection with a double track system and further illustrating in dotted lines one of the gate members arranged in safety position and in full lines in normal position.

Figure 4 is a section on line 4—4, Figure 5.

Figure 5 is a section on line 5—5, Figure 2.

Figure 6 is a section on line 6—6, Figure 5.

Figure 7 is a section on line 7—7, Figure 6.

Figure 8 is a detail illustrating the gate hanger and track therefor.

Figure 9 is a group perspective illustrating the operating means shiftable cam bars.

Figure 10 is a fragmentary view showing a hanger element.

Figure 11 is a section on line 11—11, Figure 5.

Figure 12 is a fragmentary view showing one of the operating levers.

Figures 13 and 14 are perspective views of the shiftable cam bars employed in a single track system.

Figures 15 and 16 are fragmentary views in side elevation, of the shiftable cam bars employed in connection with a double track system.

Figure 17 is a fragmentary view illustrating a modified form of shiftable cam bar.

Referring to Figure 1 of the drawings, 1 and 2 denote a pair of railway tracks of a double track railway system, and 3 designates the highway intersecting the tracks 1 and 2.

Referring to Figure 2, 4 denotes a railway track of a single track system and 5 a highway which intersects the track 4.

In connection with a safety gate in ac-

cordance with this invention, it includes a pair of gate members when the safety gate is employed in connection with a double track system or a single track system, and 5 when employed with a double track system one gate member is arranged at one side of and exteriorly of the track 1, and the other gate member is arranged at one side of and exteriorly of the track 2, and by this arrangement the gate members will close the highway 3 leading to or from the track 1, and further will close the highway 3 leading to and from the track 2. When employed in connection with a single track system, the gate members are arranged at opposite sides of the track 4 to close the highway 5 leading to and from said track 4. The pair of gate members are synchronously operated and normally are in open position and are shifted from such position to 15 close the highway.

The difference between the employment of the safety gate with respect to a double track and a single track system resides 20 mainly in the actuating means operated by the train for operating the gate members shifting mechanisms, and the housings for inclosing the actuating means operated by the train.

30 The construction and arrangement of the housings referred to are those that are employed in connection with a double track system, but with respect to a single track system the same construction of housings is 35 employed except with a slight change in each end of each of the housings and which change will be hereinafter referred to.

Arranged exteriorly of the track 1, as well 40 as exteriorly of the track 2 and extending in the same direction as said tracks, is a closed housing, and which are indicated at 6, 7, projecting from the housings 6, 7, at one end thereof is a casing formed of a horizontal portion 8 and a pair of longitudinal portions 9, 10, and with the former extending from the housing 6 and the latter from the housing 7. Projecting from the housings 6, 7, at the outer end thereof is a casing formed 45 of a horizontal portion 11 and a pair of longitudinal portions 12, 13, and with the former extending from the housing 6 and the latter from the housing 7. The portions 8 and 11 extend transversely with respect to the tracks 1 and 2 and below the same. The casings can be set up of suitable piping of 50 the desired diameter.

The shapes of the housings and casings are shown in dotted lines in Figure 1 and the side and end walls and top and bottom of 60 each of the housings can be connected together in any suitable manner. The housings and casings are positioned below the top of the track bed.

65 The top 14, at a point between its center and each inner end wall, each housing, is

provided with an opening and said openings are indicated at 16, 17 (Fig. 3).

The top of the horizontal portion 8 of one casing, is provided with a pair of rectangular slots 18, 19, and the top of the horizontal portion of the other casing is formed with a pair of rectangular slots 20, 21. The slots 18 and 20 are arranged in lengthwise alignment and the slots 19 and 21 are also arranged in lengthwise alignment. The slots 75 of each pair are positioned centrally of a track. Extending up through each of said slots is an actuating lever to be presently referred to, and the levers which extend up through the slots 18 and 21 are adapted to be actuated by an on-coming train as it approaches the crossing at the highway, and said levers are positioned a sufficient distance from the crossing so that when they are actuated they will operate the gate member shifting mechanisms whereby the gate members, to be hereinafter referred to, will be shifted to close the highway to traffic before the train reaches the crossing.

90 The actuating levers which extend up through the slots 19 and 20 are operated as the train leaves the crossing for the purpose of actuating the gate member shifting mechanisms to restore the gate members to normal position to open the highway 3 for traffic.

95 The ends of the housing 6, as well as the housing 7, are indicated at 22, and which abut against the top 14 and bottom 15 of their respective housing. The ends 22 in connection with the top 14 and bottom 15 of 100 each housing provide a chamber 23, and said ends 22 close the longitudinal portions 9, 10, 12 and 13 of the casings and further in connection with said portions provide chambers 24 and 25 at the opposite ends of a 105 housing. The slots 18 and 19 communicate with the chamber formed by the longitudinal portion 8, and the slots 20 and 21 communicate with the chamber formed by the longitudinal portion 11. The chambers 24 110 open into the portion 8 and the chambers 25 open into the portion 11.

115 As to the casings employed with respect to a single track system, the longitudinal portions of one casing are indicated at 8', 9', and the horizontal portion at 10'. The longitudinal portions of the other casing are indicated at 11', 12' and the horizontal portion at 13'. The horizontal portion 10', at 120 its top, is provided with a slot 18' and the horizontal portion 13', at its top, is provided with a slot 19'. The slots 18', 19' are arranged in alignment.

125 The following described construction and arrangement of elements apply to the safety gate construction whether employed for a double track or a single track system.

Positioned on the top 14 of the housing 6, as well as the top 14 of the housing 7, is a pair of spaced flat circular combined guide 130

and coupling members 9 consisting of a body portion 26 (Fig. 6) of substantial height provided at its bottom with a laterally extending annular flange 27, and said body portion 26, centrally thereof, is formed with an opening 28 extending from the lower face of said body portion and opening into a vertically disposed pocket 29, arranged in the upper part of the body portion 26. The pocket 29 is of greater diameter than the opening 28. The body portion 26, between the pocket 29 and its outer periphery is formed with a circular socket 30 of greater depth than the depth of the pocket 29. The socket 30 opens at the top of the body portion 26. Interposed between the flange 27 and the top 14, is a packing element 31, and the latter in connection with the body portion 26 is fixedly secured to the top 14 by hold-fast devices 32. Arranged within the pocket 29 is a packing 33, secured in position by a gland 33' and positioned within the socket 30 is a packing 34.

The opening 28 in one of the combined guide and coupling members registers with the opening 16, and the opening 28 of the other combined guide and coupling member registers with the opening 17.

Extending into the socket 30 of one of the combined guide and coupling members, is a vertically extending tube of substantial diameter and height and which is indicated at 35, and extending into the other combined guide and coupling member is a vertically disposed tube 35' of substantial diameter and height. The tubes 35 and 35' are of the same height and bear on the packings 34 within the sockets 30.

Each of the tubes 35, 35' is fixedly secured to a combined guide and coupling device, by clamping screws 37, carried by the body portion 26 and binding against the tube as clearly shown in Figure 6.

Mounted upon the upper end of each tube 35, 35', as well as extending therein, is a packing element 39 provided with a socket 40, into which extends a tube. Carried by the elements 39 are clamping screws 41 which bind against the tubes for fixedly securing the elements 39 and tubes together.

Secured to the outer side, at the upper end of each of the tubes and below the elements 39, is a band 42 to which is connected a pair of inclined stay rods 43, having their lower ends anchored, as at 45. The rods 43 maintain the tubes in vertical position.

The tube 35, as well as the tube 35', provides a plunger chamber 44, and operating therethrough is a substantially elongated plunger 46, which extends into a chamber 23 and has its lower end provided with a foot piece 47. The plunger 46 extends up through the top 14, combined guide and coupling device and up and through and above the packing element 39, and is provided with

a reduced upper terminal 48. The lower portion of the plunger 46, in proximity to the foot piece 47, is slotted, as at 49.

To make the operation of the plungers, to be hereinafter set forth, readily understood, it is thought advisable to designate the plungers when employed in connection with the double track system by the reference characters 52, 53, 54 and 55, see Figure 1, and when employed in connection with a single track system to designate the plungers 163, 164, 165 and 166, see Figure 2. The plungers 52 and 54 or 163 and 164 are synchronously operated for the purpose of shifting the pair of gate members to closed position, and the plungers 53 and 55 or 165 and 166 are synchronously operated for the purpose of shifting the gate members to open position.

The plungers 52, 54, 53 and 55 are operated when the trains are travelling in the direction of the arrows A and B, Figure 1, but the plungers 52 and 54 are operated in advance of the plungers 53 and 55. The plungers 163, 164, 165 and 166 are operated when the train is travelling in the direction of the arrows 179 and 181, see Figure 2, but the plungers 163 and 164 are operated in advance of the plungers 165 and 166.

The following described construction and arrangement of elements apply to the safety gate when employed in connection with a double or a single track system. For each system a pair of gate members is employed and associated with each gate member is a tiltable track for the purpose of shifting the gate member to closed and open position. Each of the gate members, best shown in Figure 5, consists of a rectangular body portion 72, provided at its top with a hanger 73, which is pivotally connected, as at 73' to a trolley 74, travelling on a track member. By reference to Figure 5, a gate member and track member are shown in full lines in normal position and in dotted lines when the track member has been tilted to provide for the shifting of the gate member to close the crossing. The gate member is shown in closed position in full lines. Each of the track members is clearly shown in Figure 8 and consists of a substantially elongated flat bar 75 on which the trolley 74 is mounted. The bar 75, at each terminal portion, is enlarged, as at 76, and provided with a substantially elongated slot 77 (Fig. 8) through which extends the reduced upper end of a plunger.

To provide for a clear understanding of the operation of the gate when used in connection with a double track system or a single track system, in Figure 1 of the drawings the track members are indicated at 68 and 69 and said track member 68 is mounted upon the plungers 54, 55 and track member 69 mounted on the plungers 52 and

53, and with reference to Figure 2, the track members are indicated at 155 and 156 and with the former mounted on the plungers 163 and 165 and the latter on the plungers 164 and 166.

10 The following described construction and arrangement of the elements of safety gate apply to the latter when employed in connection with a double track system or a single track system. The tubular members 35, 35' arranged on a housing 6 or 7, see Figures 5 and 6, are connected together by an upstanding bracket 79 which extends above the track members and carries a cover member 80 for inclosing the track member to protect the same from inclement weather. The cover member 80 is conoidal-shaped in cross section and closed at its top and each end and further open at its bottom. The cover member 80 is secured to the bracket 79 by the hold-fast devices 81. The length of the cover member 80 is greater than the space between the tubes 35, 35', so as to project beyond the same in a direction lengthwise 20 with respect to the track bed.

25 The bottom of each of the chambers 23 has secured thereon a series of spaced pairs of bearing brackets 82, and journalled in each pair of brackets is a transversely extending friction roller 83. See Figures 5 and 6.

30 Secured to the inner faces of the side walls of the housing 6 or housing 7, and in proximity to the brackets 82, is a longitudinally extending support of a length less than the length of the housing. The supports are indicated at 84, 85. See Figure 6. The inner side edge of each of said supports has projecting therefrom a series of friction rollers 86.

40 Mounted upon the bottom of each housing 6 or 7, centrally thereof, is a series of vertically disposed brackets 87, each provided with a vertical bearing 88.

45 Arranged within the chamber 23 formed by each housing 6 or 7, is a pair of spring controlled plunger shifting elements and the elements arranged in the housing 6 are of the same construction as those arranged 50 in the housing 7. The plunger shifting elements are positioned on the transversely extending friction rollers 83, and arranged between the friction rollers 83 carried by the supports 84, 85 and each pair of shifting elements is spaced by the bearings 88. See Figure 6. The plunger shifting elements are movable lengthwise with respect to the housing for the purpose of elevating and lowering the plungers to provide for the tilting of the track members as well as for the purpose of restoring the track members to normal position.

60 One of the plunger shifting elements in each housing is indicated at 92 and the other at 93. The plunger shifting elements 92

are synchronously operated and the plunger shifting elements 93 are synchronously operated.

65 The plunger shifting elements are best shown in Figures 13, 14, 15 and 16. When 70 the plunger shifting elements are employed in connection with a double track system, they are actuated from each end thereof, but when employed in connection with a single track system, they are actuated only 75 from one end thereof. Figures 13 and 14 illustrate the form of plunger shifting elements employed in a single track system and Figures 15 and 16 illustrate the form of 80 plunger shifting elements employed in connection with a double track system. The plunger shifting element 92, whether employed in a single or a double track system, includes a bar 123 of substantial length, provided at a point removed from each end 85 with a cam member and which are indicated at 124, 125, and are oppositely disposed with respect to each other. The outer end of the member 124 is bevelled, as at 126, and the outer end of the member 125 is bevelled, as 90 at 127. The bevelled ends 126, 127 are oppositely disposed with respect to each other. One end of the bar 123 is provided with a laterally extending eye 128.

95 The plunger shifting element 93, whether employed in connection with a single or a double track system, includes a substantially elongated bar 135, provided at one end with a cam member 136, and in proximity to its other end with a cam member 139. The inner end of the cam member 136 is bevelled, as at 137, and the inner end of the cam member 139 is bevelled as at 140. The bevelled ends 137, 140 are oppositely disposed with respect to each other. The cam member 136 carries an eye 138, and the cam member 139 is provided with an eye 143.

100 When the plunger shifting elements 92 and 93 are employed in connection with a single track system, that end of the bar 123 110 opposite the end provided with the eye 128 is provided with a substantially elongated rod 129, provided with an eye 130 and said rod 129 has its outer end connected, as at 132, to a connecting rod 168. The plunger shifting element 93 has that end of the bar 135, opposite the end provided with the cam member 136, provided with a substantially elongated rod 141 of substantial 115 length which is coupled, as at 142 to the connecting rod 169.

120 When the safety gate is set up with respect to a single track, the rod 141 of the plunger shifting element 93, at one side of the track is connected by the rod 169 to the rod 141 of the plunger shifting element 93 at the other side of the track, and said rod 169 is provided with an actuating lever 171. The rod 129 of the plunger shifting element 92, arranged at one side of the 125 130

track, is connected by the rod 168 to the rod 129 of the plunger shifting element 92 at the other side of the track, and said rod 168 is provided with an actuating lever 170. 5 By this arrangement when the lever 170 is shifted, the two plunger shifting elements 92 are simultaneously operated, and when the lever 171 is actuated the two plunger shifting elements 93 are simultaneously 10 operated.

When the plunger shifting elements 92 and 93 are employed in connection with a double track system and with reference to Figures 15 and 16, the bar 123 at each end 15 is provided with a substantially elongated rod and which are indicated at 94, 95. Pivotaly connected to the rod 94 is a link 96, and pivotaly connected to the rod 95 is a link 97. The bar 135 has projecting from 20 each end a rod of substantial length and which rods are indicated at 94', 95'. The rod 94' is pivotaly connected to a link 96' and the rod 95' is pivotaly connected to a link 97'.

25 The rods 94, 94' extend through one end wall 22 of a housing 6 or 7 and through a bearing element 92' which is secured to the outer face of the said end wall 22. The rods 95, 95' extend through the other end wall 22 30 of the housing 6 or 7 and also through a bearing element 93' which is secured to the outer face of said end wall 22.

The actuating means for the plunger shifting elements when these latter are employed in connection with a double track system, is best shown in Figure 9, and said actuating means includes a hollow shaft formed of two sections 190, 191, and a shaft 192 extending through and projecting from 40 the hollow shaft. Said hollow shaft is referred to generally by the reference character 193. Said means further includes a hollow shaft formed of two sections 194, 195, and said shaft is generally referred to 45 by the reference character 196. Said means further includes a shaft 197 which extends through the shaft 196, and is of greater length thereof. The sections 190, 191 of the shaft 193 are connected together by a slotted 50 sleeve 198. The sections 194, 195 of the shaft 196 are connected together by a slotted sleeve 199. Fixed to the shaft 192 and extending up through the slot 200 in the sleeve 198, is an actuating lever 201. Fixed to the 55 shaft 193 is an actuating lever 202. The lever 201 extends up through the slot 18, and the lever 202 extends up through the slot 19. Fixed to the shaft 197 and extending up 60 through the slot 203 in the sleeve 199, is an actuating lever 204, and fixed to the shaft 196 is an actuating lever 205. The lever 204 extends up through the slot 20 and the lever 205 up through the slot 21.

Fixed to one end of the shaft 193, is a 65 crank arm 206 having the link 96' pivotaly

connected therewith. Fixed to the other end of the shaft 193 is a crank arm 207 having the other link 96' connected therewith. The crank arms 206, 207 project upwardly from the shaft 193. Fixed to the shaft 192 70 in proximity to each end thereof, as well as depending therefrom, is a crank arm and which arms are indicated at 208, 209. Pivotaly connected to the crank arm 208 is one of the links 96 and pivotaly connected to 75 the arm 209 is the other link 96'.

Fixedly secured to and depending from each end of the shaft 196 is a crank arm and said arms are indicated at 210, 211, and to the crank arm 210 is pivotally connected the 80 link 97' and to the crank arm 211 is pivotally connected the other link 97'.

Fixedly secured to the shaft 197, in proximity to each end thereof, is an upstanding crank arm, and which are indicated at 212, 85 213, and to the former is pivotally connected one of the links 97 and to the latter is pivotally connected the other link 97'.

The two plunger shifting elements 92 are connected together and synchronously operated from the shaft 192 and from the shaft 197, and the plunger shifting elements 93 are connected together and synchronously operated from the shafts 193 and 196. 90

The links 96, 96' and shafts 192 and 193, 95 are arranged within the casing consisting of the portions 9, 10 and 11 and into the portions 9 and 10 extend the rods 94, 94'. The rods 95 and 95' extend into the portions 12 and 13 of the other casing, and the links 97, 100 97' are also arranged in said portions 12 and 13. The shafts 196, 197 are arranged within the portion 11 so that the casing includes the portions 12 and 13.

With respect to a single track arrangement, the rods 129 and connecting rod or shaft 168 are arranged in the portions 8', 9' and 10' of one of the casings, and the rods 141 and connecting rod or shaft 169 are arranged in the portions 11', 12' and 13' of 110 the other casing.

With respect to a single track arrangement, the rods 129 extend through the bearings 131 carried by the end walls 22 of the housings. The levers 170, 171 are connected with the rods 168, 169, respectively and said lever 170 is connected with the shaft 102, and the lever 171 is connected to the shaft 105. Within the portions 10' and 13' of the casings, are hangers 106, and each of which includes a pivoted link 107 provided at its lower end with a slot 108 through which extends a connecting rod. Arranged below the slot 18', as well as below the slot 19', is a hanger 113 provided with a pivot 114 for a lever 170 125 or 171 and each of said levers has an enlarged lower end 115 provided with an oval-shaped slot 116, through which extends a connecting rod 168 or 169.

The levers 170, 171, 201, 202, 204 and 205 130

extend a substantial distance above their slots so that they can be impacted by the pilot of the locomotive. By reference to Figure 5, the position of the pilot 117 is illustrated in full lines in advance of its engagement with an actuating lever, and in dotted lines when shifting the actuating lever, the latter being shown in dotted lines in shifted position. The locomotive is indicated at 118 in Figure 5.

Connected to the eye 128 is one end of a coiled spring 133, which is secured to an end wall 22. The eye 130 has attached thereto one end of a coiled spring 134, which is secured to the said end wall 22. Connected to the eye 138 is one end of a coiled spring 144, which is secured to the other end wall 22, and connected to the eye 143 is one end of a coiled spring 145 secured to the said end wall 22. The springs are employed to assist in returning the plunger shifting elements to normal position.

As before stated, the plunger shifting elements travel against the friction rollers, and also between spaced guides 147 which are secured to the lower face of the top of the housing, and connected to said spaced guides is a stop member 147' for each plunger 46, and said stop member 147' extends through the slot 49, and by this arrangement the upward movement of a plunger 46 is arrested.

An electric alarm 148' of known construction is employed to sound a warning on the shifting of the gate members to closing position.

The plungers 46, operated in a body of oil, are indicated at 148 and each of the plungers is provided with a retarding member 149 to cushion the lowering movement thereof.

The plunger shifting elements in each chamber 23 also operate in a body of oil, as indicated at 150. Bearing 150' are employed for the shafts 193 and 196.

Resilient latches 151 and 152 are provided for detachably securing the gate members in normal position, and resilient latches 153, 154 are provided for detachably securing the gate members when shifted in position to close the crossing to traffic.

In connection with the operation of the safety gate when set up in connection with a double track system, if a train is travelling in the direction of the arrow A on track 2, the lever 201 will be actuated whereby the links 96 and 96' will be shifted in the direction of the arrows C, D in Figure 1, carrying the plunger shifting elements 92 in the same direction, whereby the bevelled ends 126 engaging the foot pieces of the plungers 52 and 54 will elevate said plungers tilting the tracks 68 and 69 to the position shown in dotted lines Figure 5, whereby the gate members will shift to closing position, such as indicated in dotted lines in Figure 5, under such conditions the highway 3 will be

closed. As the train continues to move in the direction of the arrow A, the lever 204 will be actuated whereby the links 97 will be shifted in the direction of the arrows E, F, under such conditions the plunger shifting elements 92 will be carried in the direction of the arrows E, F, whereby the bevelled ends 127 of the cam members 125 will shift the plungers 53 and 55 upwardly tilting the track members 68 and 69 in the direction opposite to that to which they were tilted by the plungers 52 and 54, and under such conditions the gate members will return to normal position. Before the plunger shifting elements 92 are actuated by the operation of the lever 204, said elements have been restored to normal position by the action of the springs 133 and by the weight of the plungers 52 and 54 which move to normal position by gravity.

If a train is travelling on track 1, in the direction of arrow B, the lever 205 is actuated and the links 97' are shifted in the direction of the arrows G, H, which carry the plunger shifting elements 93 in the same direction, and when these latter are shifted by the links 97', the bevelled ends 137 of the cam members 136 elevate the plungers 52 and 54 for the purpose of tilting the track members 68 and 69 whereby the gate members will be shifted to closed position. As the train continues to travel on track 1, it will engage and actuate the lever 202, shifting the links 96' in the direction of the arrows I, J, whereby the plunger shifting elements 93 will be carried in the same direction and the bevelled ends 140 of the cam members 139 will engage and elevate the plungers 53 and 55 and tilt the track members 68 and 69 in opposite directions so that the gate members will be moved to open position.

In connection with the operation of the safety gate when used with a single track system, if a train is travelling in the direction of the arrow 179, it will engage and actuate the lever 170 whereby the plunger shifting elements 92 will be moved in the direction of the arrow L, so that the bevelled ends 126 of the cams 124 will elevate the plungers 163, 164 so that the gate members will move to closing position with respect to the crossing. As a train continues to travel in the direction of the arrow 179, it will engage and actuate the lever 171, whereby the plunger shifting elements 93 will be moved in the direction of the arrow 180 and the bevelled ends of the cam members 139 will engage the plungers 165 and 166 to elevate them for the purpose of tilting the track members 155 and 156 in the opposite direction to provide for the gates moving to open position. If the train is travelling in the direction of the arrow 181 on the track 4, it will engage and actuate the lever 171

to move the plunger shifting elements 93 in the direction of the arrow 182, whereby the bevelled ends 187 of the cams 136 will elevate the plungers 163 and 164 for the purpose of tilting the track members 155 and 156 so that the gate members will move to closing position with respect to the crossing. As the train continues to travel in the direction of the arrow 181, it will engage and actuate the lever 170 whereby the plunger shifting elements 92 will be moved in the direction of the arrow 183 so that the bevelled ends 127 of the cams 125 will engage and elevate the plungers 165 and 166, tilting the track members 155 and 156 in the opposite direction whereby the gate members will be moved to open position.

In the modified form shown in Figure 17, and which is indicated generally by the reference character 75', the construction is the same as that referred to with this exception, that the plunger shifting elements are not provided with the springs 133 and 134, 145 and 146.

From the foregoing construction and arrangement of parts, a safety gate is set up which is operated in advance of a train passing a crossing, so that when operated, the gate members will be positioned to extend transversely of the crossing and close the highway to traffic before the train passes the crossing, and furthermore as the train leaves the crossing means is provided whereby the gate members will be shifted to normal position so as to open the highway, and by setting up the safety gate in this manner it is obvious that accidents at railway crossings will be reduced to a minimum, and although the preferred embodiment of the invention is as illustrated and described, yet changes in the details of construction can be had which will fall within the scope of the invention as claimed.

What I claim is:

1. A safety gate for railway crossings comprising track members tilttable in opposite directions and positioned on opposite sides of the track bed, gate members carried by the track members for closing a highway to traffic from each side of the track bed, means operated by a train as it approaches the crossing for tilting said track members in one direction to provide for the gravity moving of the gate members to a position to close the highway to traffic from each side of the track bed, and means operated by the train as it passes the crossing for tilting said track members in the opposite direction to provide for the gravity moving of said gate members in a direction to open the highway from each side of the track bed.

2. A safety gate for railway crossings comprising track members tilttable in opposite directions and positioned on opposite sides of the track bed, gate members carried

by the track members for closing a highway to traffic from each side of the track bed, means operated by a train as it approaches the crossing for tilting said track members in one direction to provide for the gravity moving of the gate members to a position to close the highway to traffic from each side of the track bed, means operated by the train as it passes the crossing for tilting said track members in the opposite direction to provide for the gravity moving of said gate members in a direction to open the highway from each side of the track bed, and means for detachably securing said gate members in position to close the highway to traffic from each side of the track bed.

3. A safety gate for railway crossings comprising track members tilttable in opposite directions and positioned on opposite sides of the track bed, gate members carried by the track members for closing a highway to traffic from each side of the track bed, means operated by a train as it approaches the crossing for tilting said track members in one direction to provide for the gravity moving of the gate members to a position to close the highway to traffic from each side of the track bed, means operated by the train as it passes the crossing for tilting said track members in the opposite direction to provide for the gravity moving of said gate members in a direction to open the highway from each side of the track bed, and means for detachably securing said gate members in position to close the highway to traffic from each side of the track bed, and means for detachably securing the gate members in normal position.

4. A safety gate for railway crossings comprising track members tilttable in opposite directions and positioned on opposite sides of the track bed, gate members carried by the track members for closing a highway to traffic from each side of the track bed, vertically movable plungers supporting and tilting said track members, means operated by a train as it approaches the crossing for vertically moving certain of said plungers thereby tilting said track members in one direction to provide for the gravity moving of the gate members to a position to close the highway to traffic from each side of the track bed, and means operated by the train as it passes the crossing for vertically moving the other of said plungers to tilt said track members in the opposite direction to provide for the gravity moving of the gate members to open the highway to traffic.

5. A safety gate for railway crossings comprising track members tilttable in opposite directions and positioned on opposite sides of the track bed, gate members carried by the track members for closing a highway to traffic from each side of the track bed,

vertically movable plungers supporting and
tilting said track members, means operated
by a train as it approaches the crossing for
vertically moving certain of said plungers
5 thereby tilting said track members in one di-
rection to provide for the gravity moving
of the gate members to a position to close
the highway to traffic from each side of the
track bed, means operated by the train as it
10 passes the crossing for vertically moving the
other of said plungers to tilt said track
members in the opposite direction to provide
for the gravity moving of the gate members
to open the highway to traffic, and means
15 for detachably securing said gate members
in position to close the highway.

in position to close the highway.

6. A safety gate for railway crossings comprising track members tiltable in opposite directions and positioned on opposite sides of the track bed, gate members carried by the track members for closing a highway to traffic from each side of the track bed, vertically movable plungers supporting and tilting said track members, means operated by a train as it approaches the crossing for vertically moving certain of said plungers thereby tilting said track members in one direction to provide for the gravity moving of the gate members to a position to close the highway to traffic from each side of the track bed, means operated by the train as it passes the crossing for vertically moving the other of said plungers to tilt said track members in the opposite direction to provide for the gravity moving of the gate members to open the highway to traffic, means for detachably securing said gate members in position to close the highway, and means for detachably securing the gate members in normal position.

members in normal position.

7. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, and a plurality of plunger shifting elements operated by the train as it passes the crossing and provided with cam members for vertically moving the other of said plungers for tilting the track members in an opposite direction to provide for the gravity moving of the gate members to open the highway to traffic.

05 8. A safety gate for railway crossings

comprising track members tiltable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, a plurality of plunger shifting elements operated by the train as it passes the crossing and provided with cam members for vertically moving the other of said plungers for tilting the track members in an opposite direction to provide for the gravity moving of the gate members to open the highway to traffic, and means for detachably securing said gate members in position to close the highway to traffic.

9. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, a plurality of plunger shifting elements operated by the train as it passes the crossing and provided with cam members for vertically moving the other of said plungers for tilting the track members in an opposite direction to provide for the gravity moving of the gate members to open the highway to traffic, means for detachably securing said gate members in position to close the highway to traffic, and means for detachably securing the gate members in normal position.

10. A safety gate for railway crossings comprising track members tiltable in opposite directions and positioned on opposite sides of the track bed, gate members carried by the track members for closing a highway to traffic from each side of the track bed, vertically movable plungers supporting and tilting said track members, means operated by a train as it approaches the crossing for vertically moving certain of said plungers thereby tilting said track members in one direction to provide for the gravity moving of the gate members to a position to close

- the highway to traffic from each side of the track bed, means operated by the train as it passes the crossing for vertically moving the other of said plungers to tilt said track members in the opposite direction to provide for the gravity moving of the gate members to open the highway to traffic, means for detachably securing said gate members in position to close the highway, 5 means for detachably securing the gate members in normal position, and anti-friction rollers for supporting said plunger shifting elements.

11. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, a plurality 20 of plunger shifting elements operated by the train as it passes the crossing and provided with cam members for vertically moving the other of said plungers for tilting the track members in an opposite direction to provide 25 for the gravity moving of the gate members to open the highway to traffic, and anti-friction rollers for supporting said plunger shifting elements.

12. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, a plurality 40 of plunger shifting elements operated by the train as it passes the crossing and provided with cam members for vertically moving the other of said plungers for tilting the track members in an opposite direction to provide for the gravity moving of the gate members to open the highway to traffic, and anti-friction rollers for supporting said plunger shifting elements.

13. A safety gate for railway crossings comprising track members tilttable in opposite directions and positioned on opposite sides of the track bed, gate members carried by the track members for closing a highway 45 to traffic from each side of the track bed, vertically movable plungers supporting and tilting said track members, means operated by a train as it approaches the crossing for vertically moving certain of said plungers thereby tilting said track members in one direction to provide for the gravity moving of the gate members to a position to close the highway to traffic from each side of the track bed, means operated by the train as it passes the crossing for vertically moving the other of said plungers to tilt said track members in the opposite direction to provide for the gravity moving of the gate members to open the highway to traffic, means for detachably securing said gate members in position to close the highway, means for detachably securing the gate members in normal position, anti-friction rollers for supporting said plunger shifting elements, and anti-friction rollers engaging one side of each of said plunger shifting elements.

14. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving certain of said plungers to shift said track members in one direction to provide for the gravity moving of the gate members to a position to close the highway to traffic from each side of the track bed, a plurality 50 of plunger shifting elements operated by the train as it passes the crossing and provided with cam members for vertically moving the other of said plungers for tilting the track members in an opposite direction to provide for the gravity moving of the gate members to open the highway to traffic, anti-friction rollers for supporting said plunger shifting elements, and anti-friction rollers engaging one side of each of said plunger shifting elements.

15. A safety gate for railway crossings comprising track members tilttable in opposite directions and positioned at opposite sides of a track bed, gate members movable on said track members for closing a highway to traffic from each side of the track bed, vertically movable plungers supporting and tilting said track members, a plurality of plunger shifting elements operated by a train as it approaches the crossing and provided with cam members for vertically moving

ing certain of said plungers to shift said track members in one direction to provide for the gravity moving of the gate members to a position to close the highway to traffic from each side of the track bed, a plurality of plunger shifting elements operated by the train as it passes the crossing and provided with cam members for vertically moving the other of said plungers for tilting the track members in an opposite direction to provide for the gravity moving of the gate members to open the highway to traffic, means for detachably securing said gate members in position to close the highway to traffic, anti-friction rollers for supporting said plunger shifting elements, and anti-friction rollers engaging one side of each of said plunger shifting elements.

16. A safety gate for railway crossings comprising track members tiltable in opposite directions and positioned on opposite sides of the track bed, gate members carried by the track members for closing a highway to traffic from each side of the track bed, means operated by a train as it approaches the crossing for tilting said track members in one direction to provide for the gravity moving of the gate members to a position to close the highway to traffic from each side of the track bed, means operated by a train as it passes the crossing for tilting said track members in opposite directions to provide for the gravity moving of said gate members in a direction to open the highway from each side of the track bed, and a protective means inclosing said track members.

17. A safety gate for railway crossings comprising track members tiltable in opposite directions and positioned on opposite sides of the track bed, gate members carried by the track members for closing a highway to traffic from each side of the track bed, means operated by a train as it approaches the crossing for tilting said track members in one direction to provide for the gravity moving of the gate members to a position to close the highway to traffic from each side of the track bed, means operated by a train as it passes the crossing for tilting said track members in opposite directions to provide for the gravity moving of said gate members in a direction to open the highway from each side of the track bed, means for detachably securing said gate members in position to close the highway to traffic from each side of the track bed, and a protective means inclosing said track members.

18. A safety gate for railway crossings comprising track members tiltable in opposite directions and positioned on opposite sides of the track bed, gate members carried by the track members for closing a highway to traffic from each side of the track bed, means operated by a train as it approaches the crossing for tilting said track members

in one direction to provide for the gravity moving of the gate members to a position to close the highway to traffic from each side of the track bed, means operated by the train as it passes the crossing for tilting said track members in opposite directions to provide for the gravity moving of said gate members in a direction to open the highway from each side of the track bed, means for detachably securing said gate members in position to close the highway to traffic from each side of the track bed, means for detachably securing the gate members in normal position, and a protective means inclosing said track members.

19. A safety gate for railway crossings comprising opposed vertically movable plungers arranged at one side of the track bed, opposed vertically movable plungers arranged at the other side of the track bed, shiftable gate members for closing a highway to traffic from each side of the track bed, means operated by said plungers to provide for the shifting of said gate members to a position to close the highway and from such position, and plunger shifting elements operating in opposite directions and operated by a train as it approaches and passes the crossing for vertically moving said plungers to provide for the operation of said gate shifting means, each of said plungers provided with cam members riding against the lower ends of said plungers for vertically moving them.

20. A safety gate for railway crossings comprising opposed vertically movable plungers arranged at one side of the track bed, opposed vertically movable plungers arranged at the other side of the track bed, shiftable gate members for closing a highway to traffic from each side of the track bed, means operated by said plungers to provide for the shifting of said gate members to a position to close the highway and from such position, plunger shifting elements operating in opposite directions and operated by a train as it approaches and passes the crossing for vertically moving said plungers to provide for the operation of said gate shifting means, and means for detachably securing the gate members in position to close the highway to traffic.

21. A safety gate for railway crossings comprising opposed vertically movable plungers arranged at one side of the track bed, opposed vertically movable plungers arranged at the other side of the track bed, shiftable gate members for closing a highway to traffic from each side of the track bed, means operated by said plungers to provide for the shifting of said gate members to a position to close the highway and from such position, plunger shifting elements operating in opposite directions and operated by a train as it approaches and

- passes the crossing for vertically moving said plungers to provide for the operation of said gate shifting means, each of said plungers provided with cam members riding against the lower ends of said plungers for vertically moving them, and means for detachably securing the gate members in position to close the highway to traffic. 55
22. A safety gate for railway crossings comprising opposed vertically movable plungers arranged at one side of the track bed, opposed vertically movable plungers arranged at the other side of the track bed, shiftable gate members for closing a highway to traffic from each side of the track bed, means operated by said plungers to provide for the shifting of said gate members to a position to close the highway and from such position, plunger shifting elements operating in opposite directions and operated by a train as it approaches and passes the crossing for vertically moving said plungers to provide for the operation of said gate shifting means, means for detachably securing the gate members in position to close the highway to traffic, and means for detachably securing said gate members in normal position. 60
23. A safety gate for railway crossings comprising opposed vertically movable plungers arranged at one side of the track bed, opposed vertically movable plungers arranged at the other side of the track bed, shiftable gate members for closing a highway to traffic from each side of the track bed, means operated by said plungers to provide for the shifting of said gate members to a position to close the highway and from such position, plunger shifting elements operating in opposite directions and operated by a train as it approaches and passes the crossing for vertically moving said plungers to provide for the operation of said gate shifting means, each of said 65
- 45 plungers provided with cam members riding against the lower ends of said plungers for vertically moving them, means for detachably securing the gate members in position to close the highway to traffic, and means for detachably securing said gate members in normal position. 70
24. In a safety gate for railway crossings a pair of synchronously operated shiftable elements, each positioned at one side of a track bed and each providing means for operating a gate member actuating mechanism to move a gate member to closure position, a pair of synchronously operated shiftable elements, each positioned at one side of a track bed and each provides means for operating the gate member actuating mechanism to move the gate member to open position, each of the elements of the first pair formed intermediate its ends with a pair of oppositely disposed cam members, and each of the elements of the second pair provided at each end with a cam member and with the cam members oppositely disposed with respect to each other. 75
25. In a safety gate, opposed vertically movable spaced plungers arranged at one side of a track bed, opposed vertically movable spaced plungers arranged at the other side of the track bed, track members mounted on said plungers and tilted in opposite directions thereby, gate members suspended from said track members and gravity movable to closure position when the track members are tilted in one direction and to open position when the track members are tilted in the opposite directions, said plungers movable downwardly by gravity, means for moving certain of the plungers upwardly to tilt the track members in one direction, means for moving the other of the plungers upwardly to tilt the track members in the opposite direction, and means for cushioning the downward movement of the plungers. 80
26. A railway crossing gate of the class described comprising a support, a tiltable carrier mounted on the support, a gate slidably mounted on the carrier, carrier actuating means in the track-way adjacent the crossing and operatively connected with the carrier to actuate the same, and train operated means in the track-way remote from the crossing for controlling said carrier actuated means. 85
27. A railway crossing gate of the class described comprising a tilting gate carrier, and two sets of trip devices located respectively close to and remote from the crossing and having means for alternately actuating said carrier to shift the gate into operative and inoperative position. 90
- In testimony whereof, I affix my signature hereto.

EDWARD JAMES HUNT.
